UNITED STATES PATENT OFFICE.

CHARLES MÜNDEL, OF BALTIMORE, MARYLAND.

ROTARY REACTION-MOTOR.

SPECIFICATION forming part of Letters Patent No. 735,561, dated August 4, 1903.

Application filed June 10, 1903. Serial No. 160,850. (No model.)

To all whom it may concern:

Be it known that I, CHARLES MÜNDEL, a citizen of the United States, residing at Baltimore, State of Maryland, have invented certain new and useful Improvements in Rotary Reaction-Motors, of which the following is a specification.

My invention relates to improvements in rotary reaction-motors, and has for its object to provide a motor of this class which shall be simple and cheap in construction and practical in its operation.

The invention consists in the novel construction and combination of parts, as herein-after described, and pointed out in the appended claim.

The accompanying drawings illustrate the invention, in which—

Figure 1 illustrates a vertical longitudinal sectional view through the motor, and Fig. 2 shows a central vertical cross-section of the same. Fig. 3 is a detail of the steam-supply tube.

In the drawings the housing or casing is cylindrical and comprises two half-cylindrical sections *a* and *a'*, which in the present instance are provided with abutting flanges *b* and *b'*, by means of which the said two sections are secured together. The lower section *a'* of the casing is provided with an integral base having laterally-projecting flanges *c*, on which the casing rests. Suitable bearings *d* are provided in the casing at each side for supporting a hollow shaft *e*, which extends centrally through the casing and projects on the exterior thereof at either side. A pulley *f* is secured on one end of the hollow shaft on the exterior of the casing, and the other end of said shaft on its interior is provided with a shoulder *g*, and from said shoulder to its end the shaft is provided with internal screw-threads *h*. A bushing *i* fits into one end of the shaft *e* and is provided with exterior screw-threads which engage the threads *h* on the interior of said shaft. The bushing *i* is also provided with a central smooth bore, through which a stationary

tube *j* passes into the end of the hollow shaft *e*. The end of this tube *j* is provided with a head or flange *j'*, one side of which seats against the shoulder *g* on the interior of the shaft *e* and the bushing *i* takes against the other side of said head or flange and holds the tube in place and makes a tight joint. In operation the tube *j* remains stationary, while the bushing and shaft revolve.

The hollow shaft *e* is provided with a central coupling-head *k*, having a passage which is in communication with the hollow shaft, and one end of a coiled tube *l* is secured to the said shaft *k* and is coiled therefrom, each succeeding coil *l'* having an increased side as compared with the inner coil nearest the said shaft. The outermost or largest coil of the tube is provided with an abrupt bend *l''*, and the extreme end of said tube is turned backward *U*-shaped and in a direction parallel with the coils *l'*. This abrupt bend *l''* in the end of the out-coil forms an abutment against which the steam or air strikes immediately before it is discharged at the turned-back end *l''* and aids in driving the tube forward. An outlet-pipe *m* in the bottom of the casing serves as an exhaust from the casing. It will be seen that the steam or air (whichever may be used) passes through the coiled tube in the same direction that the tube turns, as indicated by darts, and that this course is maintained until it strikes the abutment formed by the abrupt bend *l''*, where the course of the steam or air is changed and directly reversed. This abrupt change in the course of the steam or air increases the speed and force of the revolution of the motor.

I am aware that it has heretofore been proposed to provide rotary motors with metal wheels having scroll-shaped passage-ways; but as far as I am aware I am the first to provide a coiled tube having one end of its spiral connected to and in communication with a hollow shaft and the outermost end of the spiral being free and having a *U*-shaped bend near its discharge end, whereby to abruptly reverse the course of the steam or air.

Having thus fully described my invention, what I claim as new, and desire to secure by Letters Patent, is—

In a rotary motor the combination of a hollow revolute shaft, and a coiled tube secured at one end to and in communication with said hollow shaft, each succeeding coil having an increased size as compared with the inner coil nearest the said shaft, and the outermost

coil provided with an abrupt bend turned backward **U** shape and having a discharge-outlet beyond said bend.

In testimony whereof I affix my signature in the presence of two witnesses.

CHARLES MÜNDEL.
